US00D719088S

(12) **United States Design Patent**
Koebler

(10) **Patent No.:** **US D719,088 S**
(45) **Date of Patent:** **** Dec. 9, 2014**

(54) **12-POST STARTER BATTERY**

(71) Applicant: **Martin Koebler**, Davidson, NC (US)

(72) Inventor: **Martin Koebler**, Davidson, NC (US)

(**) Term: **14 Years**

(21) Appl. No.: **29/469,328**

(22) Filed: **Oct. 9, 2013**

(51) **LOC (10) Cl.** **13-02**

(52) **U.S. Cl.**

USPC **D13/104**

(58) **Field of Classification Search**

(57) **CLAIM**

The ornamental design for a 12-post starter battery, as shown and described.

DESCRIPTION

FIG. 1 is an isometric view of the invented 12-post starter battery showing the new design;

FIG. 2 is a top view thereof;

FIG. 3 is a front view thereof;

FIG. 4 is a rear view thereof.

FIG. 5 is a bottom view thereof; and,

FIG. 6 is a right end view thereof, the left end view being a mirror image thereof.
